UNITED STATES PATENT OFFICE.

CHARLES R. STORZ, OF BROOKLYN, NEW YORK.

SCISSORS.

Application filed August 6, 1921. Serial No. 480,332.

To all whom it may concern:

Be it known that I, CHARLES R. STORZ, a citizen of the United States, residing at New York, in the borough of Brooklyn, county of Kings, and State of New York, have invented certain new and useful Improvements in Scissors; and I do hereby declare the following to be a full, clear, and exact description of the same, reference being had to the accompanying drawings, forming part of this specification.

This invention relates to scissors and shears having detachable blades and relates particularly to the method of securing the cutting blade to the shear arm. The principal object of the present invention is to provide a simple and efficient method of securing the cutting blade to the cutting arm. One of the features of the present invention is the use of a stud having lateral extensions as the principal attaching means for securing the cutting blade to the arm, and the secondary features of the invention lie in the additional means for holding the blade in position on the pivot, irrespective of the particular kind of pivot used in securing the two shear arms together, since the main pivot of the shears is not necessarily relied upon in any way to secure the cutting blades in position.

The device here illustrated is of particular importance in surgical scissors, but the invention is not limited in any way to such use, many of the styles of this cling-blade type being intended for regular general or domestic use.

The thought of having detachable blades to a pair of scissors or shears, is not new with the present invention, having been previously proposed, but as far as I am aware, it is new to secure the cutting blades to the arms by a positive lock, consisting of a French pivot spaced away from the main pivot of the arms and by using one or more lugs to prevent displacement of the cutting blade about its pivot, relying on the resiliency of the metal to insure a snug fit of the blade on its arm. By "French pivot" I mean the stud element of a French lock, such pivot having a circular portion and also having a non-circular head usually diamond-shape, double convex or elliptical, and in the French lock the other element has a slot which exactly fits the head of the stud in one position, and when the two

elements are turned on the pivot the pivot forms the connection or lock.

In the drawings herewith, I have shown two of the many modifications of the invention, one of the modifications showing a transverse stud forming the French pivot and having a slot and an integral struck out lug on the blade, and the other showing a longitudinal stud and having a perforation in the blade to engage a pin integral with or secured to the arm. In each of the examples illustrated, the securing pivot is located somewhat near the center of the blade, which I find to be by far the best practice. It will be understood, of course, that my invention contemplates the use of a securing pivot at any point whatsoever on the blade, as, for example, at a point near the outer end of the blade, provided the scissors are of the blunt point type. It will also be obvious that two or more pins may be provided to prevent rotation of the cutting blade about the securing pivot, although, in practice, a single locking means has always been found ample.

In the drawings,—

Figure 1 is a general or plan view of a pair of scissors, in accordance with the present invention.

Fig. 2 is a view of the scissors disassembled and showing the inner faces of both blades.

Fig. 3 is a transverse vertical section through the main pivot of the scissors.

Fig. 4 is a similar view through the securing pivot.

Fig. 5 is a view taken through the center of the integral locking lug of the cutter blade.

Fig. 6 is a longitudinal sectional view taken through the two pivots and the locking lug.

Fig. 7 is a view similar to Fig. 6, but showing a modification which employs a locking pin on the shear arm, instead of a locking lug on the cutting blade, as in Fig. 6.

The frame of the shears is of the usual type ending in finger grips 11 and 12 on the shear arms 14 and 15, which, in the present invention, may be made of relatively soft steel or alloy metal, since they serve no other purpose than to carry the cutting blades 16 and 17 which are of thin steel of high grade and are not ordinarily intended

to be resharpened, since they can be replaced at a less cost than the usual price of sharpening a pair of shears.

In the embodiment shown in Figs. 1 and 6, the arms 14 and 15 of the frame are secured together by means of a French pivot consisting of an elliptical head 18 rising from a cylindrical stud 19 which may be integral with the arm 14, but for manufacturing reasons is usually separate and then riveted or otherwise secured to the arm. The head of this stud fits a spherical recess 20 in the arm 15, such recess having an opening therein of the same size and elliptical shape as the plan of the head 18. This French pivot is not new with me and neither is this particular use of the French pivot to form the main pivot of the pair of shears new at the present time, although it is new as a means for securing the cutting blade to the arm, and it is also new to strike out a spherical recess for the French pivot, so that the struck out portion will engage the recess below the head of the pivot. For certain types I prefer to use the ordinary screw pivot to secure the arms together.

In Fig. 2 the elliptical or rather double convex head 23 of the securing pivot has its major axis transverse to the length of the shear arm, whereas, in the modification shown in Fig. 7, the similar head 24 has its major axis parallel to the length of the arm, and since, in the modification, the main pivot is a screw, it is unnecessary to provide a slot similar to the slot 25 in the cutting blade 16, this slot being preferable to the large size opening that would be required to clear the main pivot 19 and also avoiding the bending of the blade to the large extent that would be necessary if the cutting blade were required to pass over the main pivot stud.

At the outer end the blade 16 is provided with a locking lug 29 which is formed by punching two parallel slits in the blade and bowing out the metal between the slits into the shape best seen in Fig. 6. A relatively long shallow groove 30 is cut in the metal of the arm to receive this lug 29. As usual in the art, the contour of the cutting blade follows exactly the contour of the shear arm having the usual rounded point 32 and the triangular inner end 33.

Referring particularly now to Fig. 5, it will be noted that the metal of the blade 16 is punched down on either side of the slot 34, forming a spherical depression 35 on the top face of the blade and forming a similar spherical projection 36 on the side of the blade engaging the shear arm 14. This construction is of considerable importance, as it not only avoids weakening the blade by counter-sinking, but it provides a much more efficient joint with ample metal for final shaping by grinding without cutting

below the level of the top of the pivot. The slot 34 in plan view is of the same size and shape as the plan view of the head 23, so that the cutting blade may be placed transversely to the shear arm to fit over the head 70 of the French pivot and upon turning the blade about such pivot a very snug engagement will be had. As soon as the blade and arm are parallel the locking lug 29 will snap into the groove 30 and the blade and 75 arm will then be found to be in close contact throughout the entire length of the blade, the form of the blade being such as to cause the cutting blade to cling to the shear arm.

In the modification shown in Fig. 7, the locking lug 29 is replaced by a small cylindrical pin 40 secured to or integral with the shear blade 41, such pin engaging a circular hole 42 in the cutting blade 43. As previously stated, the relative location of the locking pin 42 and the securing pivot 24 may be reversed, but the form illustrated is believed to be the most advantageous and desirable.

What is claimed is:

1. A detachable cutting blade having a concave recess and a non-circular orifice through a portion of said recess.
2. A detachable cutting blade having a spherical depression with an elliptical orifice therein, said recess and orifice forming part of a pivotal connection.
3. A detachable cutting blade for a scissor arm having a plurality of perforations therethrough, one of said perforations being adapted to receive the non-circular head of a pivotal stud to secure the blade to the scissor arm.
4. A detachable cutting blade for a scissor arm having a pivot socket for securing said blade to the arm, an orifice to receive the main pivot of the scissor and an additional means co-operating with said scissor arm to lock the blade against rotation about said pivot.
5. In a cutter, a pair of shear arms, a pivot for said arms, a detachable resilient cutting blade for each shear arm, a securing pivot on each arm for the attached blade, and projection-and-recess means for locking each of said blades against rotation about its securing pivot.
6. A shear arm for use with detachable blades, characterized by the provision of a cylindrical blade-securing pivot having a non-circular head, said pivot being spaced from the main pivot of the shears.
7. A detachable cutting blade for a scissor arm characterized by the provision of a spherical projection pressed out to one side of the blade and having a non-circular opening therein, the greatest length of said opening being substantially equal to the diameter of the projection.

8. A detachable sheet metal cutting blade for a scissor arm characterized by the provision of a main pivot receiving opening, a secondary or securing pivot opening, and an integral stuck-out portion to form a resilient means for locking said blade against rotation about said secondary pivot.
9. A detachable sheet metal cutting blade for a scissor arm characterized by the provision of a main pivot receiving opening near one end of the blade, an integral lug near the other end of the blade, and a pressed out projection between said opening and said lug and slotted to receive a locking pivot.
10. A scissor or shear shank having a projection provided with an elongated portion having an inclined edge, and a blade to fit on said shank and provided with an elongated opening to receive said projection, the greater dimension of said opening extending at a substantial angle to the greater dimension of said projection when the blade is assembled lengthwise on the shank, a wall of said opening along its greater dimension having an inclined portion to cooperate with the inclined portion of the projection, the outer surface of the blade being unobstructed by the projection, the blade being pivotally retained by said projection on the shank in different angular positions of the blade thereon.
11. A scissor or shear shank having a projection provided with an elongated portion having an inclined edge, and a blade to fit on said shank and provided with an elongated opening to receive said projection, the greater dimension of said opening extending at a substantial angle to the greater dimension of said projection when the blade is assembled lengthwise on the shank, a wall of said opening along its greater dimension having an inclined portion to cooperate with the inclined portion of the projection, the outer surface of the blade being unobstructed by the projection, the blade being pivotally retained by said projection on the shank in different angular positions of the blade thereon, and means on the shank to engage the blade to prevent dis-assembling of the blade and shank without lateral displacement of the blade.
12. A scissor or shear shank provided with a projection having an elongated portion extending crosswise of the shank and
- having an inclined edge extending lengthwise of the shank, and a blade having an elongated opening extending lengthwise of the blade and provided with an inclined wall to cooperate with said inclined edge, means to prevent edgewise motion of the blade on the shank in either direction, the blade being rotative in two directions for assembling on the shank relatively to said projection, the blade being rotatively retained by the projection on the shank in different angular positions while being assembled on the shank.
13. A scissor or shear shank provided with a projection having an elongated portion extending crosswise of the shank and having an inclined edge extending lengthwise of the shank, and a blade having an elongated opening extending lengthwise of the blade and provided with an inclined wall to cooperate with said inclined edge, the blade being rotative relatively to said projection for assembling on the shank, the shank having one or more pins and the blade having one or more holes to receive said pins, said projection retaining the blade on the shank and the pin or pins retaining the blade from edgewise displacement on the shank, the blade requiring flexing laterally to admit the pins in said holes and to release the blade from the pins.
14. A scissor or shear shank having a projection, and a blade to fit lengthwise on said shank, said blade having an opening to rotatively receive said projection, said projection and opening having cooperating means to retain the blade on the shank with the blade lengthwise and in different angular positions on the shank, the blade being rotative in two directions relatively to the shank to assemble and dis-assemble them.
15. A scissor or shear shank having a projection, and a blade to fit lengthwise on said shank, said blade having an opening to rotatively receive said projection, said projection and opening having cooperating means to retain the blade on the shank with the blade lengthwise and in different angular positions on the shank, and means on the shank to engage the blade to prevent dis-assembling thereof without lateral displacement thereof, said means retaining the blade from edgewise displacement when in operative position on the shank.

CHARLES R. STORZ.
